[57] CLAIM

The ornamental design for a combined desk and lamp therefor, substantially as shown and described.

DESCRIPTION

FIG. 1 is a top plan view of combined desk and lamp therefor showing my new design;

FIG. 2 is a front elevational view thereof;

FIG. 3 is a right side elevational view thereof, the left side being a mirror image thereof; and

FIG. 4 is an enlarged perspective view of the combined desk and lamp therefor with the desk top in extended position.
